[57] CLAIM

The ornamental design for an ornamental child's pillow in the fanciful form of an elephant, as shown and described.

DESCRIPTION

FIG. 1 is a perspective view of the pillow taken from above the left front corner;

FIG. 2 is a top plan view thereof;

FIG. 3 is a perspective view thereof taken from below the right rear corner; and,

FIG. 4 is a bottom plan view thereof.

The stippled shading represents conventional fabric and is understood to extend uniformly throughout the areas represented.
